DESIGN FOR A TOOTHBRUSH HOLDER

Earl A. Stein, San Francisco, Calif.

Application January 8, 1944, Serial No. 112,193

Term of patent 3½ years

(Cl. D4—3)

To all whom it may concern:

Be it known that I, Earl A. Stein, a citizen of the United States and a resident of the city and county of San Francisco, State of California, have invented a new, original, and ornamental Design for a Toothbrush Holder, of which the following is a specification, reference being had to the accompanying drawing, forming a part thereof.

I claim:

The ornamental design for a toothbrush holder, as shown.

EARL A. STEIN.
